UNITED STATES PATENT OFFICE.

PAUL WALLENSTEIN, OF VENUS, NEBRASKA.

MACHINE FOR TURNING DOWN SPINDLES FOR WAGON-AXLES.

SPECIFICATION forming part of Letters Patent No. 734,639, dated July 28, 1903.

Application filed October 29, 1902. Serial No. 129,190. (No model.)

To all whom it may concern:

Be it known that I, PAUL WALLENSTEIN, a citizen of the United States, and a resident of Venus, county of Knox, and State of Nebraska, have invented a new and useful Improvement in Machines for Turning Down Spindles for Wagon-Axes, of which the following is a specification, the principle of the invention being herein explained and the best mode in which I have contemplated applying that principle, so as to distinguish it from other inventions.

My invention relates to hand-operated devices for turning down worn wagon or buggy spindles.

The object of my said invention is a provision of means whereby such turning down of the spindle may be effected without removing the axle from the vehicle to which it is attached.

Said invention consists of means hereinafter fully described, and specifically set forth in the claims.

The annexed drawings and the following description set forth in detail certain mechanism embodying the invention, such disclosed means constituting but one of various mechanical forms in which the principle of the invention may be used.

In said annexed drawings, Figure I represents a front elevation, partly broken away, of a device embodying my invention, illustrating same mounted upon the vehicle-axle. Fig. II represents a vertical axial cross-sectional view of the front of the frame, showing the forming-surface for guiding the cutting-tool, the spindle-axis and the inner portions of the cutting device being also therein shown, together with means for holding such cutting device firm; and Fig. III represents a vertical section of the device, taken upon a plane indicated by the line 3-3, Fig. I, and viewed as indicated by the arrow in said figure.

A frame A is formed with a shank a, which is adapted to be secured to the under side of the axle B by two clamps C C, provided with hand-screws c c, which bear against the under surface of the shank, whereby the latter, as will be readily understood, may be securely fastened to the axle. The end of said shank is provided with hand-screw a', which

bears upon the under side of the axle. Upon the outer end of the frame is formed an extension A'. The outer end of this extension is provided with an internally-threaded bearing a². In alignment with the bearing a² is a second internally-threaded bearing a³, formed in the outer end of the intermediate frame portion A². This intermediate frame portion is provided or formed with two small arms a⁴ a⁴, which carry upon their inner ends a barrel a⁵, provided with an internal frustoconical forming-surface a⁶, which is coaxial with the bearings a² and a³, the inclination of the said surface to the said axis being equal to that of the bearing-surface upon the spindle-axis which it is desired to impart to such spindle. The inner end of said barrel is provided with an aperture a⁹, coaxial with the bearings a² and a³ and the forming-surface a⁶. This aperture is of a diameter such as to freely admit the axle-spindle and is surrounded by the neck a⁷, projecting from the end of the barrel, having three set-screws a⁸ passing therethrough, as shown, whereby the spindle may be adjusted relatively to the barrel-axis, as will be readily understood.

A threaded shaft D is journaled in the bearings a² and a³, its outer end being provided with an end crank d, screwed thereto. The inner end of said shaft is provided with an arm D', pivoted upon the carrying-piece d', so as to be capable of oscillation toward and from the barrel-axis. The inner end of such oscillatory arm is provided with a roller d², engaging the forming-surface a⁶, such inner end being provided with a cutting-tool d³. The shaft is formed with an axial bore d⁴, in which slides a rod E, whose inner end is provided with an internally-threaded portion e, which is adapted to be screwed upon the threaded end b' of the axial spindle b.

Two extensible supports F F have their sliding members f f mounted upon the frame A, preferably upon the shank and that portion immediately below the barrel. These supports carry the weight of the device and the vehicle during the operation of turning. A convenient form of support is that shown in the drawings, in which the lower end of the sliding member f is provided with a series of transverse holes and extends into the

interior of the hollow base f' , which is provided with a transversely-removable bolt f^2 , which may be caused to pass through each one of the holes in the arm f , as will be readily understood.

In applying the above-described device the frame is mounted upon the axis and the latter is supported by the supports F , the clamps C being left loose and the axle-spindle b projecting into the barrel a^5 . For adjustment the set-screws a^3 are now turned so as to cause the spindle-axis to intersect the middle of the aperture a^9 in the end of the barrel. The hand-screw a' is now turned in the required direction, so as to incline the frame upon said screws as a fulcrum, thereby causing the axis of the spindle to become coaxial with the axis of the barrel. It is thus seen that the angular relationship of the frame, and hence of the barrel-axis, may be changed to bring the said spindle into coaxial relationship with the barrel. This is often necessary, for the reason that the spindles frequently become bent under usage. The rod E is slid toward the axle, and its end is screwed upon the end of the spindle, as shown in Fig. II. The tool d^3 having been adjusted to give the required diameter to the spindle when finished and the clamps tightened to secure the frame firmly to the axle, the device is ready for operation. This is effected by turning the crank d , whereby the shaft is automatically fed forward and the tool guided by the roller d^2 in contact with the frame-surface a^6 . The rod E acts as a support and guide for the inner end of the shaft D , whereby it prevents said inner end from springing, and so impairing the action of the cutting-tool. The rod E being readily removable, other rods may be substituted therefor having internally-threaded ends conforming with various sizes of the threaded axial ends, as will be readily understood, so that the device may be used for various sizes of spindles. To cause the wheel-hub bearings to receive the newly-turned axle-spindle, such hub is provided with a bushing having the required diameter.

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention—

1. In means for turning down axle-spindles, the combination of a frame arranged to be removably secured to the axle, a revoluble cutting device including a hollow rotatable shaft and a rod slidable on said shaft, said rod being securable to the end of the axle for steadyng said cutting device.

65 2. In means for turning down axle-spindles, the combination of a frame arranged to

be removably secured to the axle, a revoluble cutting device including a hollow shaft and an oscillatory member carrying the cutting-tool; and a rod slidale in said shaft and securable to the end of the axle for steadyng the cutting device, said frame provided with a forming-surface for engaging said oscillatory member.

3. In means for turning down axle-spindles, the combination of a frame arranged to be secured to the axle, a revoluble cutting device consisting of a threaded shaft mounted in and having threaded engagement with said frame, and an oscillatory arm secured to said shaft and carrying a cutting-tool; and means for supporting the end of said shaft to which said member is secured during its advance.

4. In means for turning down axle-spindles, the combination of a frame arranged to be secured to the axle, a revoluble cutting device consisting of a threaded shaft mounted in and having threaded engagement with said frame, and an oscillatory arm secured to said shaft and carrying a cutting-tool; and means securable to the end of the axle for supporting the end of said shaft to which said member is secured.

5. In means for turning down axle-spindles, the combination of a frame arranged to be secured to the axle, a revoluble cutting device consisting of a threaded shaft mounted in and having threaded engagement with said frame, and an oscillatory arm secured to said shaft and carrying a cutting-tool; and means securable to the end of the axle for supporting the end of said shaft to which said member is secured, said frame provided with a forming-surface for engaging said oscillatory member.

6. In means for turning down axle-spindles, the combination of a frame arranged to be secured to the axle, a revoluble cutting device consisting of a threaded shaft provided with an axial bore, and an oscillatory arm secured to the inner end of said shaft carrying a cutting-tool; and a rod slidale in said bore and securable to the end of the axle-spindle for supporting such inner shaft end, said frame provided with a forming-surface for engaging said oscillatory member.

7. In means for turning down axle-spindles, the combination of a frame arranged to be secured to the axle and to extend beyond the end thereof, a cutting device consisting of a threaded driving crank-shaft provided with an axial bore and mounted in said frame, and an oscillatory arm carrying a cutting-tool; and a rod slidale in said bore and securable to the end of the axle-spindle, said frame provided with a forming-surface engaging the end of said arm and with means for centering such surface relatively to the axle-axis.

8. In means for turning down axle-spindles, the combination of a frame provided with a shank at one end, a threaded bearing

on the other end, means for securing said shank to the end of the axle, a threaded driving crank-shaft provided with an axial bore, extending into the portion of the frame in-

5 intermediate of said shank and extension and journaled in said bearing, an oscillatory arm carrying a roller and a cutting-tool, and a rod securable to the end of the axle-spindle extending into and slidably in said bore, said

intermediate frame portion provided with a forming-surface engaging the roller upon said arm, and with an aperture for admitting the axle-spindle.

Signed by me this 22d day of October, 1902.
PAUL WALLENSTEIN.
